UNITED STATES PATENT OFFICE

ADAM RAMBACHER, OF MUNICH, GERMANY

RAILROAD PERMANENT WAY CONSTRUCTION

Application filed March 18, 1929, Serial No. 347,897, and in Germany March 22, 1928.

A cross-sleeper railroad track of wood and concrete, the wooden ties being carried in concrete where they meet the rails, is known. The cross-sleepers run transversely over the track in its entire width, conveying disturbances from one side of the track to the other, if not in so high a degree as cross-ties generally. In addition, the concrete beds break, as experience has shown, at a length of 70 cm.

The principal aim of the present invention is to avoid these disadvantages. It is furthermore intended to attain connection between the individual parts which is as safe as possible, elastic, which protects vehicles and rails in the best way, simple and easy to provide and to take apart again. At the same time, however, an effortless regulation of the rail-level should be had without employing a tamping pick, with its destructive effect on the ballasting material.

In railroad permanent way of wood and concrete, the concrete supports are, for this purpose, each formed of two concrete blocks, arranged with a suitable gap which is bridged over by the wooden sleeper, which is connected with the blocks and the tie-plate in a dismountable manner. The jaws of the tie-plate which hold the rail are raised, and the holding-clips, carried in niches in the jaws and serving to fasten the rail in position, are extended to the exterior, so that the supporting metal or boards, to be laid under the rails in order to compensate for the difference in level in the road, as well as the rails themselves are held laterally at any level of the jaws.

The invention is illustratively exemplified in the accompanying drawings, in which, Figure 1 is a substantially transverse sectional view of a road bed; Figure 2 is a plan view of a section of the road bed; Figure 3 is a transverse sectional view of a rail and tie plate; and Figure 4 is a top plan view of the tie plate.

Referring to the drawings and particularly Figures 1 and 2, each concrete support consists of two concrete blocks a and a' , spaced apart a suitable distance and bridged over by a wooden tie b of about

5-6 cm. in thickness. The concrete blocks a and a' , about 35 x 35 cm. in length and breadth, provide an entire surface on the roadbed of one side of the track of about 2,500 sq. cm., thus being able to carry the heaviest wheel pressure, providing that the roadbed of the track is made sufficiently firm, which is ensured by previous rolling or ramming.

The concrete blocks are furnished with a groove holding a prominence a^2 in the center, for the reception of the wooden tie b . The tie b is provided with notches corresponding to these prominences a^2 , so that longitudinal displacement of the tie is impossible. The latter, as may be seen from Figs. 1 and 2, projects laterally over the two concrete blocks a and a' sufficiently to enable it to be carried by the workmen.

It has exactly the same width as the tie-plate c , so that it is completely covered by the latter, in order to prevent the formation of water deposits.

The connection between the tie-plate, the wooden tie and the concrete blocks a and a' is made by means of screw-bolts d , which engage nuts d' . The latter are let into the concrete blocks a and a' from beneath and are enclosed suitably in felt so as to protect the concrete.

The so formed bridge now carries the running rail e between two highly-curved jaws c' of the tie-plate c . Both foot bolts f on the interior and the exterior fix the running rail e by means of holding-clips g in the usual way (Fig. 3).

The latter, however, are, as may be seen from Figs. 3 and 4, embedded in niches in the jaws c' and extended exteriorly far enough to enable the level of the running rail e to be regulated in a high degree by the insertion of one or more supporting metal shim plates or boards w to be laid between the jaws c' . In this way it is made possible for even the slightest sinking in a supporting bridge to be compensated for without anything further. The high jaws c' and long holding-clips g are especially useful in allowing the running rail to be regulated as to its level, such regulation being effected

by using of a longer foot-screw, of approximately 3 cm., so that adjustment of the elevation of the supporting bridge itself would not be necessary only after some years of wear.

8 The holding of the track to the gauge is effected by means of cast iron members *h*, which are suitably positioned as shown in Figure 1 and fastened with four screws *h'* and clip-plates *h*² to the feet of the rails *e*.

10 Where wooden ties as described above cannot be used, e. g. on account of the ravages of ants, the correspondingly moulded concrete blocks are bridged over with iron supports, which are provided with soft covering, lining the points of contact.

Claims for patent.

1. In a railway track structure, the combination with a pair of rails, of separate pairs of concrete blocks arranged along said track, the blocks of each pair being spaced apart transversely of a rail, a wood tie piece spanning each pair of blocks, and a tie plate separably attached to each pair of blocks, 25 the wood tie and to the rail to support the latter on the tie above the space between the blocks of a pair.

2. A railway track structure, as claimed in claim 1, in which the tie plate is provided 30 with pairs of spaced upstanding lugs embracing opposite sides of the rail base, and clamping members adjustable between the pairs of lugs against the base of the rail at one end and against the tie plate beyond the 35 lugs, at the other end.

3. A railway track structure, as claimed in claim 1, in which the tie plate is provided with pairs of spaced upstanding lugs on opposite sides of the rail base, clamping 40 members having arched ends disposed between the pairs of lugs and disposed against the base of the rail, the opposite ends of the members being straight and disposed against the tie plate beyond the lugs, shim plates between the rail and tie plate and means projecting upwardly between the lugs of each pair and through the clamping member to clamp the latter against the rail base, shim plates and tie plate.

4. In a railway track structure in which the rail is adjustably supported upon its tie plates, the combination therewith of separate pairs of concrete blocks arranged along said tracks, the blocks of each pair being spaced apart transversely of a rail, a wood tie piece spanning each pair of blocks, and a tie plate separably attached to each pair of blocks, the wood tie and to the rail to support the latter on the tie above the space 55 between the blocks of a pair.

In testimony whereof I hereunto affix my signature:

ADAM RAMBACHER.
